UNITED STATES PATENT OFFICE

FRANK F. BURTON, OF MOUNT CARMEL, CONNECTICUT, ASSIGNOR TO WINCHESTER REPEATING ARMS CO., OF NEW HAVEN, CONNECTICUT, A CORPORATION OF DELAWARE

TRIGGER MECHANISM FOR FIREARMS

Application filed April 22, 1929. Serial No. 356,984.

This invention relates to an improvement in trigger-mechanisms for firearms and particularly to that class of firearms in which the firing-pin or its equivalent exerts a constant effort to swing the sear out of cocking engagement with it, in which position the said sear is releasably retained by the trigger; such a type of trigger-mechanism being shown in United States Patent No. 132,222, granted 10 October 15, 1872, to F. Von Martini, and United States Patent No. 145,118, granted December 2, 1873, to Daniel Moore.

One of the objects of my invention is to provide a simple, reliable and durable trigger-mechanism of the class described, constructed with particular reference to smoothness and certainty of operation.

Another object of my invention is to provide a trigger-mechanism of the class described having a smooth and adjustable travel of the trigger for releasing the firing-element of the firearm.

With the above objects in view, my invention consists in a trigger-mechanism for firearms, having certain details of construction and combinations of parts as will be hereinafter described and particularly recited in the claims.

In the accompanying drawings:

30 Fig. 1 is a broken view, partly in elevation and partly in vertical longitudinal section of a firearm provided with my improved trigger-mechanism, the parts being shown in the positions due them when the gun is cocked, ready for firing;

Fig. 2 is a corresponding view but showing the parts in the positions due them after the actuation of the trigger for the release of the firing-pin;

40 Fig. 3 is a transverse sectional view taken on the line 3—3 of Fig. 1;

Fig. 4 is a detached perspective view of the sear;

45 Fig. 5 is a corresponding view of the trigger; and

Fig. 6 is a similar view of the assembly-yoke.

In carrying out my invention as herein shown, I employ a pivotal sear 10 located between the forwardly-extending complemen-

tary side-arms 11 and 12 of a sheet-metal assembly-yoke 13 which is secured by means of a screw 14 to the underside of the receiver 15 of the arm.

The sear 10 above referred to is mounted 55 at its forward end upon a pin 16 extending transversely therethrough and between the arms 11 and 12 of the assembly-yoke 13.

At its rear end the sear 10 is formed with an upstanding sear-nose 17, the rear upper corner 18 of which is forwardly and upwardly inclined and is adapted to engage a similarly inclined cam-like latching-shoulder 19 formed upon the underside of the reciprocating firing-pin 20, which latter is of usual form and requires no detailed description other than to say that it is urged forward by the usual firing-pin spring 21 housed within it and is itself housed within a reciprocating bolt 22 provided with an oscillatable 60 bolt-handle 23.

The slope of the rear upper corner 18 of the sear-nose 17 and the slope of the shoulder 19 of the firing-pin 20 are of such degree with reference to the pivot-pin 16 that the forward urge of the firing-pin 20 under the tension of its spring 21 tends to rock the sear 10 downward against the counter-urge of a sear-spring 24 mounted in a pocket 24^a 75 in the upper face of a forwardly-offsetting portion 25 of the said sear 10 and impinging at its upper end against the adjacent underface of the receiver 15 (Fig. 2).

To releasably retain the sear 10 in position to prevent the forward movement of the firing-pin 20, as shown in Fig. 1 of the drawings, I provide a horizontal sear-supporting shoulder 26 offsetting from the rear face of the upper arm 27 of a pivotal trigger 28 mounted upon a pin 29 extending transversely between the depending complementary arms 30 and 31 of the assembly-yoke 13, and formed with the usual curved finger-piece 32 projecting below the firearm.

The shoulder 26 of the trigger 28 is adapted to engage the underface 33 of the sear 10 adjacent the rear wall of a vertical slot 34 formed therein and receiving the upper end of the arm 27 of the trigger 28, as clearly shown in the drawings.

5 A trigger-spring 35 having its lower end seated in a pocket 36 of the trigger finger-piece 32 and having its upper end encircling a finger 37 depending from the rear wall 10 of the assembly-yoke 13, exerts a constant effort to swing the trigger counter-clockwise and hence yieldingly maintain the shoulder 26 thereof beneath the surface 33 of the sear, as shown in Fig. 1 of the drawings.

10 To limit the rearward movement of the upper end of the arm 27 of the trigger and hence the degree to which the shoulder 26 thereof underlies the surface 33 of the sear, I mount in the rear end of the said sear an 15 inclined abutment-screw 38 reduced at its forward end to form a stop-finger 39 projecting forward into the slot 34 and adapted to be engaged by the rear face of the arm 27 of the trigger to limit the rearward swing thereof.

20 For the purpose of swinging the sear 10 downward completely out of the path of the bolt 22 so as to permit its withdrawal from the firearm, I form the upper forward 25 face of the arm 27 of the trigger 28 with a cam-surface 40 adapted to co-act with a pin 41 extending transversely across the slot 34 in the said sear.

25 With the parts of my improved trigger mechanism in the positions shown in Fig. 1 of the drawings, a slight rearward draft upon the finger-piece 32 of the trigger 28 will serve to move the shoulder 26 thereof forward out of engagement with the surface 33 of the sear 10. Now, owing to the inclination of the cam-like latching-shoulder 19 of the firing-pin 20 and the inclination of the rear upper corner 18 of the sear-nose 17, the urge of the firing-pin spring 21 will act 40 to cam the sear 10 downward against the counter-urge of the spring 24 and thus permit the firing-pin to move forward and fire the cartridge in the chamber (not shown) of the firearm. The parts will have thus assumed the positions in which they are shown 45 in Fig. 2 of the drawings.

50 Now, after the discharge of the arm as above described, when the firing-pin is restored to the position in which it is shown in Fig. 1, the sear-spring 24 will be permitted to act to swing the sear clockwise to again interpose the sear-nose 17 in the path of the shoulder 19 of the firing-pin and in so doing will also permit the upper arm 27 of the 55 trigger 28 to swing rearward under the urge of the trigger-spring 35 and re-locate the shoulder 26 beneath the surface 33 of the sear.

60 The parts are now restored to the positions shown in Fig. 1 of the drawings, preparatory to another discharge of the firearm.

65 It will be noted that the distance which the shoulder 26 of the trigger 28 underlies the surface 33 of the sear 10 is determined by the degree to which the stop-finger 39

of the adjusting-screw 38 projects into the slot 34 and hence the degree to which the said trigger must be pulled before releasing the sear. Thus, if it is desired to increase the degree to which the trigger must be pulled before releasing the sear, the screw 38 may be backed out of the sear so as to permit the shoulder 26 of the trigger to ride further under the surface 33. If, on the other hand, a slighter degree of trigger-pull is desired 75 to release the sear, the screw 38 will be advanced so as to cause its stop-finger to project further within the slot 34 of the sear.

I claim:

1. In a bolt-action firearm, the combination with a vertically-slotted sear pivoted at its forward end in the firearm structure; of a firing-pin formed in its underside with an inclined cam-like latching-shoulder adapted to be engaged by a portion of the said sear and to cam the same into its releasing position; and a pivotal trigger having its upper end extended into the slot in the said sear and provided with a shoulder adapted to underlie a portion of the said sear to releasably hold the same in engagement with the latching-shoulder of the said firing-pin against the counter-urge of the firing-pin spring.

2. In a firearm, the combination with a vertically-slotted sear pivoted at its forward end in the firearm structure; of a firing-pin formed in its underside with an inclined cam-like latching-shoulder adapted to be engaged by a portion of the said sear and to cam the same into its releasing position; a pivotal trigger having its upper end extended into the slot in the said sear and provided with a shoulder adapted to underlie a portion of the said sear to releasably hold the same in engagement with the latching-shoulder of the said firing-pin against the counter-urge of the firing-pin spring; and an adjusting-screw mounted in the rear end of the said sear and projecting into the slot therein to engage the upper end of the said trigger to adjustably limit the rearward swing thereof.

In testimony whereof, I have signed this specification.
